US00D329433S

United States Patent [19]

Wilson

[11] Patent Number: Des. 329,433

[45] Date of Patent: ** Sep. 15, 1992

[54] ANTENNA MAST

D. 286,043 10/1986 Peterson D14/230
3,944,722 3/1976 Larsen ..... 343/715 X

[75] Inventor: James W. Wilson, Henderson, Nev.

Primary Examiner—Theodore M. Shooman
Attorney, Agent, or Firm—Arthur Freilich; Robert D.
Hornbaker; Leon D. Rosen

[73] Assignee: Wilson Antenna Inc., Las Vegas,
Nev.

[57] CLAIM

The ornamental design for an antenna mast, as shown
and described.

DESCRIPTION

FIG. 1 is a front elevational view of an antenna mast
showing my new design, the rear and sides being identi-
cal;

FIG. 2 is a top plan view thereof; and,
FIG. 3 is a bottom plan view thereof.

The broken line showing of the antenna whip in FIG. 1
is for illustrative purposes only and forms no part of the
claimed design.

[**] Term: 14 Years
